UNITED STATES PATENT OFFICE.

JOHN F. SULLENBERGER, OF COLUMBUS, GEORGIA.

DRYING-MACHINE.

1,216,880.

Specification of Letters Patent. Patented Feb. 20, 1917.

Application filed May 6, 1916. Serial No. 95,848.

To all whom it may concern:

Be it known that I, JOHN F. SULLENBERGER, a citizen of the United States, residing at Columbus, in the county of Muscogee 5 and State of Georgia, have invented new and useful Improvements in Drying-Machines, of which the following is a specification.

The invention relates to drying machines, 10 and more particularly to the class of rotary drying machines for grain or minute substances or materials.

The primary object of the invention is the provision of a machine of this character 15 wherein the drying pans or sections are stacked and readily interchangeable so that any one section or pan will fit upon another and in event that the capacity of the machine is to be varied for increasing or 20 decreasing the capacity the sections or pans can be added to or discarded.

Another object of the invention is the provision of a machine of this character 25 wherein hominy, grits, meal, grain and various materials can be thoroughly dried therein, the drying sections or pans being heated from coils through which circulates steam, and said sections or pans being incased so as to retain the heat therein for the 30 thorough drying of the materials after the introduction thereof at the head or top of the machine, which dried material is discharged from the bottom of said machine.

A further object of the invention is the 35 provision of a machine of this character wherein the construction thereof is novel in form and the carriers or feeders for the materials are also novel in form so that the trend of the material will be in zigzag 40 fashion from the top to the bottom of the machine so that the thorough drying of the material will be effected.

A still further object of the invention is the provision of a machine of this character 45 which is simple in construction, thoroughly reliable and efficient in operation, strong, durable and inexpensive in manufacture.

Other objects will be in part obvious and 50 in part hereinafter set forth.

The invention accordingly consists in the features of construction, combination of elements and arrangement of parts which will be exemplified in the construction herein-

after described, and the scope of the application of which will be indicated in the appended claims.

In the accompanying drawings:

Figure 1 is a side elevation of a machine constructed in accordance with the invention;

Fig. 2 is a top plan view thereof;

Fig. 3 is a fragmentary vertical sectional elevation taken through the upper portion of the machine;

Fig. 4 is a view similar to Fig. 3, taken through the lower portion of the machine;

Fig. 5 is a sectional view on the line 5—5 of Fig. 1;

Fig. 6 is a sectional view on the line 6—6 70 of Fig. 1;

Fig. 7 is a bottom plan view of the machine;

Fig. 8 is a plan view of one of the rotary agitator carriers or feeders;

Fig. 9 is a plan view of one of the pans.

Similar reference characters indicate corresponding parts throughout the several views of the drawings.

Referring to the drawings in detail, A 80 designates a casing preferably made in section and from sheet metal, the sections of which are detachably fastened together in any suitable manner, and within this case is arranged the machine, which comprises a 85 plurality of superposed annular rings 10, each being formed with outer peripheral flanges 11 through which are passed at intervals bolts 12, the same being also passed through spacer sleeves 13 arranged between 90 the flanges and the rings adjacent each other, and in this manner the rings are united in series. Each ring 10 has at its lowermost edge an internal annular supporting flange 14 upon which rests a drying pan or section 95 15 adapted to be riveted or otherwise secured to the flange, and upon the under face of the pan or section 15 are bridge straps 16 which support directly beneath the said pan or section a steam coil 17, it being understood, 100 of course, that the coils are arranged in series correspondingly to the series of pans or sections 15 and are connected together so that steam entering one of the coils will circulate through the said coils of the series, the steam being supplied thereto from any suitable source, and the condensation is delivered to the boiler or other steam gener-

ator constituting the supply for the live steam to the coil.

Extending centrally through the pans or sections 15 is a vertical shaft 18, the lower 5 end of which is journaled in a boxing or bearing 19 fitted within a supporting spider 20 formed with base feet 21, and this spider is connected to the series of rings through the medium of the base ring 22, as shown, 10 while at the top of the series of rings is a head 23 formed with a center bearing 24 for the shaft 18, which latter has fitted on its upper end a beveled gear 25 meshing with a pinion 26 fixed to one end of a drive 15 shaft 27 journaled in bearings 28 supported by the head 23, the shaft 27 being driven in any suitable manner.

Detachably fastened to the shaft 18 and movable therewith over the top surfaces of 20 the pans or sections 15 are alternately arranged series of agitator spirals or feeders 29 and 30, respectively, which act upon the material delivered to the machine, the feeders 29 being designed to work the material 25 to the center of the machine, while the feeders 30 serve to work the material outwardly to the periphery of the machine, and the coils circulating the steam heat the pan or sections 15 for the drying of the material 30 during its zigzag course from the top of the machine to the bottom thereof.

The pans or sections 15 alternately are formed with peripheral and central discharge apertures 31 and 32 respectively, so 35 that the material will be discharged from one pan at the periphery thereof and from another pan at the center thereof, thereby taking a zigzag course by the action of the series of spirals 29 and 30 thereon from the 40 top of the machine to the bottom thereof so that the material will be thoroughly dried before it is delivered from said machine at the bottom thereof. The case A serves to retain the heat within the machine and the top 45 or head 23 is formed with diametrically opposed openings 33 which permit the escape of moisture from the material and also permit the introduction of the material on to the uppermost pan 15 within the machine 50 from hoppers or other containers, while the material at the bottom of the machine is discharged therefrom into a chute or other conveyer through the delivery aperture 34 in the lowermost pan or section 15 of the 55 series.

On each spiral 29 and 30 are fixed angularly disposed wings or blades 35 which serve as agitators for the material acted upon by the spirals. Each spiral 29 and 30 is formed with a spider brace 36, which materially strengthens the same and the hub of each spiral 37 is fastened to the shaft 18 through the medium of a set screw 38 which is threaded in the hub.

65. From the foregoing description, taken in

connection with the accompanying drawings, the construction and operation of the herein described drying machine will be readily apparent and, therefore, a more extended explanation has been omitted.

Having thus described my invention, I claim:

1. A drier of the character described comprising a plurality of rings having internal and external flanges, spacers arranged between the outer flanges adjacent each other for disposing the rings in superposed relation to one another, means for fastening the flanges and spacers together, pans supported upon the internal flanges in the respective rings and having openings centrally and peripherally in alternate relation, means beneath each pan for heating the same, and feeders arranged to travel over the pan for advancing materials to the openings therein. 75

2. A drier of the character described comprising a plurality of rings having internal and external flanges, spacers arranged between the outer flanges adjacent each other for disposing the rings in superposed relation to one another, means for fastening the flanges and spacers together, pans supported upon the internal flanges in the respective rings and having openings centrally and peripherally in alternate relation, means beneath each pan for heating the same, and feeders arranged to travel over the pan for advancing material to the openings therein, and a casing concentrically of the rings. 90

3. A drier of the character described comprising a plurality of rings having internal and external flanges, spacers arranged between the outer flanges adjacent each other for disposing the rings in superposed relation to one another, means for fastening the flanges and spacers together, pans supported upon the internal flanges in the respective rings and having openings centrally and peripherally in alternate relation, means beneath each pan for heating the same, feeders arranged to travel over the pan for advancing materials to the openings therein, a casing concentrically of the rings, and means for rotating the feeders simultaneously with each other. 100

4. A drier of the character described comprising a plurality of rings having internal and external flanges, spacers arranged between the outer flanges adjacent each other for disposing the rings in superposed relation to one another, means for fastening the flanges and spacers together, pans supported upon the internal flanges in the respective rings and having openings centrally and peripherally in alternate relation, means beneath each pan for heating the same, feeders arranged to travel over the pan for advancing materials to the openings therein, a casing concentrically of the rings, means for rotating the feeders simultaneously with 110

each other, each feeder being in the form of a spiral, and deflector wings at intervals throughout the length of the spiral.

5. A drier of the character described comprising a plurality of rings having internal and external flanges, spacers arranged between the outer flanges adjacent each other for disposing the rings in superposed relation to one another, means for fastening the flanges and spacers together, pans supported upon the internal flanges in the respective rings and having openings centrally and peripherally in alternate relation, means beneath each pan for heating the same, feeders arranged to travel over the pan for advancing materials to the openings therein, a casting concentrically of the rings, means for rotating the feeders simultaneously with each other, each feeder being in the form of a spiral, deflector wings at intervals throughout the length of the spiral, and means for supplying a heating fluid to the first named means.
20. A drier of the character described comprising a plurality of rings having internal

and external flanges, spacers arranged between the outer flanges adjacent each other for disposing the rings in superposed relation to one another, means for fastening the flanges and spacers together, pans supported upon the internal flanges in the respective rings and having openings centrally and peripherally in alternate relation, means beneath each pan for heating the same, feeders arranged to travel over the pan for advancing materials to the openings therein, a casting concentrically of the rings, means for rotating the feeders simultaneously with each other, each feeder being in the form of a spiral, deflector wings at intervals throughout the length of the spiral, means for applying a heating fluid to the first named means, and supports on the pan for the heating means.

In testimony whereof I affix my signature. 45

JOHN F. SULLENBERGER.
